UNITED STATES PATENT OFFICE.

GUST HARMOUTH, OF YALE, OKLAHOMA.

ENVELOPE.

Application filed February 3, 1927. Serial No. 165,640.

This invention relates to envelopes for sending photographs and other similar matter through the mail; and it consists in constructing the envelope, as hereinafter fully 5 described and claimed, so that the same envelope can be used either for printed matter or for a written letter, at will.

In the drawings, Figure 1 is a rear view of an envelope constructed according to this 10 invention, showing the flaps folded over but not sealed. Fig. 2 is a similar view but shows the two flaps raised. Fig. 3 is a rear view but shows the flaps sealed down to enclose a letter, the tongue of the front flap 15 being straightened out and secured to the rear flap. Fig. 4 is a cross-section, taken 20 on the line 4-4 in Fig. 1, and shows the folds separated a little, for clearness. Fig. 5 is a rear view similar to Fig. 2, but shows a differently shaped envelope which has lateral projections on the tongue of its front flap.

The front and back of the envelope are 25 secured together by flaps 10, or in any other approved way. The front or address side 12 of the envelope is provided with a flap 14 having a tongue 15 at its middle part. The flap 14 is adapted to be folded over the back 16, and the back 16 is provided with 30 a flap 17 having a slot 18. The tongue 15 is thrust through the slot 18, and then is bent over and doubled, as shown in Figs. 2 and 4. This is usually sufficient to retain photographs in the envelope. The rear flap 17 is 35 provided with adhesive material 19 around its edge for securing it to the back 16. When thus secured, or partially secured, to the back the folded tongue can be withdrawn from the slot by inserting a small piece of 40 wire or wood between the front flap and the rear flap, but the tongue is not so easily withdrawn as when the rear flap is not sealed or is only partially sealed.

The envelope can be used for a letter when 45 the tongue is folded and the rear flap is completely sealed down by the adhesive material. If however it is desired to seal the

envelope securely, the tongue is left straight after passing it through the slot, and is then secured by the adhesive material on the rear 50 flap, as shown in Fig. 3.

In the modification shown in Fig. 5, the front flap 14' has lateral projections 20 on its tongue 15' which is thrust through the slot 18' of the rear flap 17'. These projections 20 are folded on the dotted lines 21 before the tongue is thrust through the slot, and are subsequently opened out again so as to retain the tongue. This envelope can be sealed by its rear flap as hereinbefore described. The tongue 15' can be made long enough to be overlapped and secured by the adhesive material on the rear flap, in a similar manner to the tongue 15, if desired, but this is not usually necessary unless the projections are shaped to permit them to be withdrawn through the slot when the rear flap is sealed to the back of the envelope. 65

What I claim is:

1. An envelope sealed at three edges and 70 having a normally open fourth edge, the front of the envelope being provided with a relatively short flap arranged at the said open edge and provided with a foldable fastening tongue, and the back of the envelope 75 being provided with a rear flap of greater length than the aforesaid flap, said rear flap being arranged at the said open edge and provided with adhesive material and having a slot in which the said tongue is 80 slideable, said tongue when straight being long enough to project from under the rear flap and being adapted to be sealed to the back of the envelope by the adhesive material on the rear flap, and being withdrawable from 85 the slot when folded.

2. An envelope as set forth in claim 1, the said fastening tongue having also foldable projections on its sides to hinder its withdrawal from the slot. 90

In testimony whereof I have affixed my signature.

GUST HARMOUTH.
